UNITED STATES PATENT OFFICE.

JOSEPH A. COSTELLO, OF CLEVELAND, OHIO, ASSIGNOR TO CLEVELAND CAR SPECIALTY COMPANY, OF CLEVELAND, OHIO, A CORPORATION OF OHIO.

CAR-ROOF.

1,053,710.

Specification of Letters Patent. Patented Feb. 18, 1913.

Application filed August 26, 1912. Serial No. 717,038.

To all whom it may concern:

Be it known that I, JOSEPH A. COSTELLO, a citizen of the United States of America, residing at Cleveland, in the county of 5 Cuyahoga and State of Ohio, have invented certain new and useful Improvements in Car-Roofs; and I hereby declare the following to be a full, clear, and exact description of the invention, such as will enable 10 others skilled in the art to which it pertains to make and use the same.

This invention relates to improvements in car-roofs, and pertains more especially to an improved car-roof-construction comprising a trough extending transversely and forming a transverse member of a car-roof and arranged below the joint formed between two metal roofing-sheets which extend over said trough and laterally of said 20 trough in opposite directions and are connected together by a cap extending longitudinally of said trough.

The object of this invention is to adequately obstruct the passage of water to said 25 trough from between the bottom of said cap and said roofing-sheets and render flooding of said trough impossible, and to have the component parts of my improved construction so relatively shaped and arranged as to 30 facilitate their manufacture and assemblage and permit expansion and contraction of the roofing-sheets.

With this object in view, and to the end of attaining any other advantage herein- 35 after appearing, this invention consists in certain features of construction, and combinations and arrangement of parts, herein-after described, pointed out in the claims, and illustrated in the accompanying draw- 40 ings which is a view, partly in section and partly in perspective, of a portion of a car-roof embodying my invention.

Referring to said drawings, A indicates roof-boards which are supported in any ap- 45 proved manner from the frame (not shown) of a car-roof embodying my invention. The application of said roof-boards to a car-roof frame is too well known in the art to require illustration and description in this 50 specification. Suffice it to state that said roof-boards are shown arranged longitudinally of the car-roof.

B indicates a metal trough resting on the

roof-boards A and arranged transversely of the car-roof. The trough B forms a 55 transverse member of the car-roof and is adapted to be secured in place at the ends (not shown).

Two metal roofing-sheets D and D rest at opposite sides respectively of the trough B 60 on the roof-boards A and extend laterally of and outwardly from opposite sides respectively of said trough and also extend longitudinally of said trough.

Each roofing-sheet D at the adjacent side 65 but externally of the trough B has a side member having an upright lower portion d extending longitudinally of the trough B. Said lower portion d of said side member of each roofing-sheet is arranged opposite and 70 spaced from the lower portion of the corresponding side member of the other roofing-sheet. Said lower portions of said side members of the roofing-sheets are shown arranged at opposite sides respectively and 75 externally of and spaced from the trough B. Said side member of each roofing-sheet has an ogee-curved portion 5 which projects or extends laterally over the trough B toward and into contact with the corresponding 80 ogee-curved portion 5 of the other roofing-sheet. The laterally extending ogee-curved portion 5 of said side member of each roofing-sheet extends longitudinally of said side member and consequently longitudinally of 85 the trough B and forms a trough 6 which depends into and extends longitudinally of the trough B and is adapted to conduct off water received thereby. The illustrated troughs 6 of the roofing-sheets have their 90 lower portions spaced apart, as at 7, and adjacent sides of said troughs 6 are extended upwardly, as at 8, above the passageways formed in and by said troughs, and the upward extensions 8 of said sides of said 95 troughs abut and press laterally against each other.

By the construction hereinbefore de- 100 scribed, it will be observed that the joint formed between the upward extensions 8 of 105 adjacent sides of the troughs 6 of the roofing-sheets are arranged above but centrally between the sides of the trough B so as to insure the dripping into said last-mentioned trough of any water which may have access to and drip from said joint. It will also

be observed that the relative arrangement of the parts hereinbefore described permit expansion and contraction of the roofing-sheets longitudinally of the car-roof without interfering with the joint formed between the upward extensions 8 of adjacent sides of the troughs 6 of the roofing-sheets.

The trough B is shown arranged therefore between and spaced from the opposing sides of the lower portions *d* of the aforesaid side members of the roofing-sheets, and a metal cap H, which is inverted-U-shaped in cross-section, covers said side members and of course covers the ogee-curved and trough-forming portions of said side members and overlaps and somewhat presses against the other sides of said lower portions of said side members below said ogee-curved and trough-forming portions and between the latter and the lower ends of said side members of the roofing-sheets and holds said side members together at the joint formed between the upward extensions 8 of adjacent sides of the troughs 6 of said side members.

The cap H is provided at the bottom and externally with two laterally and outwardly projecting flanges *h* and *h* arranged at opposite sides respectively of the cap and overlapping the bodies of the roofing-sheets without interfering with the expansion and contraction of said roofing-sheets.

Preferably the cap H has the lower portions of its sides diverging downwardly below the joints formed between the cap and the aforesaid side members of the roofing-sheets, and the aforesaid lower portions 4 of said side members of the roofing-sheets diverge downwardly between and are spaced from the inner surfaces of the lower portions of the sides of the cap, and the spaces 10 formed at said surfaces between the cap and the roofing-sheets extend from the bottoms of the flanges of the cap upwardly toward the joints formed between the cap and the roofing-sheets and form passageways which extend longitudinally of the trough B and are adapted to receive and conduct off water driven into said space at the under sides of the flanges *h* of the cap.

By the construction hereinbefore described, it will be observed that a suitable joint is not only formed between the upward extensions 8 of adjacent sides of the troughs 6 of the roofing-sheets but between the aforesaid side member of each roofing-sheet and the cap H below the ogee-curved and trough-forming portion of said side member of said roofing-sheet, so that any water driven or forced into said cap at the bottom of the flanges of the cap and received by the passageways or spaces 10 which are arranged below the joints formed between said cap and the roofing-sheets shall encounter considerable obstruction before it can enter the

trough 6, and the location of said troughs 6 above said last-mentioned joints is not unimportant in permitting as little water as possible to have access to the joint formed between the roofing-sheets.

What I claim is:—

1. The combination, with a trough forming a transverse member of a car-roof, of two metal roofing-sheets extending laterally of and outwardly from opposite sides respectively of said trough, each roofing-sheet being provided adjacent said trough with a side member which extends longitudinally of said trough and has an upright lower portion arranged opposite and spaced from the lower portion of the corresponding side member of the other roofing-sheet, said side members of the roofing-sheets projecting laterally above their said lower portions toward and into contact with each other, and a cap which is inverted-U-shaped in cross-section and covers said side members of the roofing-sheets and has its sides forming joints with said lower portions of said side members below the joint formed between said side members, said cap being provided at the bottom and externally with two laterally and outwardly projecting flanges and having the lower portions of its sides diverging downwardly below the aforesaid joints formed between the cap and the roofing-sheets, and the aforesaid lower portions of said side members of the roofing-sheets diverging downwardly between and spaced from the inner surfaces of the lower portions of the sides of the cap, the spaces formed at said surfaces between the cap and the roofing-sheets extending from the bottoms of the flanges of the cap upwardly toward the last-mentioned joints.

2. The combination, with a trough forming a transverse member of a car-roof, of two metal roofing-sheets extending laterally of and outwardly from opposite sides respectively of said trough, each roofing-sheet being provided adjacent said trough with a side member which extends longitudinally of said trough and has an upright lower portion arranged opposite and spaced from the lower portion of the corresponding side member of the other roofing-sheet, said side members of the roofing-sheets having ogee-curved portions which project laterally toward and into contact with each other, and a cap which is inverted-U-shaped in cross-section and covers said side members of the roofing-sheets and has its sides forming joints with the lower portions of said side members below the ogee-curved portions of said side members.

3. The combination, with a trough forming a transverse member of a car-roof, of two metal roofing-sheets extending laterally of and outwardly from opposite sides respectively of said trough, each roofing-sheet pro-

- vided adjacent said trough with a side member which extends longitudinally of said trough and has an upright lower portion arranged opposite and spaced from the lower portion of the corresponding side member of the other roofing-sheet, said side member of each roofing-sheet having a portion which projects laterally over the aforesaid trough and forms a trough extending longitudinally of the first-mentioned trough, and a cap which is inverted-U-shaped in cross-section and covers said side members of the roofing-sheets and has its sides forming joints with the aforesaid lower portions of said side members of the roofing-sheets between the bottom of the cap and the troughs of the roofing-sheets.
4. The combination, with a trough forming a transverse member of a car-roof, of two metal roofing-sheets extending laterally of and outwardly from opposite sides respectively of said trough, each roofing-sheet provided adjacent said trough with a side member which extends longitudinally of said trough and has an upright lower portion arranged opposite and spaced from the lower portion of the corresponding side member of the other roofing-sheet, said side members of said roofing-sheets having portions extending laterally toward and into contact with each other above said lower portions of said side members and over said trough, said laterally extending portions of said side members of the roofing-sheets having troughs which extend longitudinally of the first-mentioned trough and are arranged between the aforesaid lower portions of said side members and the joint formed between the roofing-sheets, and a cap covering said side members of the roofing-sheets and forming joints with the aforesaid lower portions of said side members between the bottom of the cap and the troughs of said side members.
5. In a car-roof, two metal roofing-sheets having each a side member which has an upright lower portion arranged opposite and spaced from the lower portion of the corresponding side member of the other roofing-sheet, said side members extending laterally above their said lower portions toward and into contact with each other; a trough arranged between the opposing sides of and spaced from said lower portions of said side members of the roofing-sheets, and a cap which is inverted-U-shaped in cross-section and covers said side members of the roofing-sheets and has its sides overlapping and in contact with the other sides of said lower portions of said side members of the roofing-sheets below the joint formed between the roofing-sheets, said cap being provided externally with two laterally and outwardly projecting flanges and having the lower portions of its sides diverging down-
- wardly below the joints formed between the cap and said side members of the roofing-sheets, and the aforesaid lower portions of said side members diverging downwardly directly between the inner surfaces of the lower portions of the sides of the cap but spaced from said surfaces.
6. In a car-roof, two metal roofing-sheets having each a side member which has an upright lower portion arranged opposite and spaced from the lower portion of the corresponding side member of the other roofing-sheet, said side members extending laterally above their said lower portions toward and into contact with each other; a trough arranged between the opposing sides of and spaced from said lower portions of said side members of the roofing-sheets, and a cap which is inverted-U-shaped in cross-section and covers said side members of the roofing-sheets and has its sides forming joints with the other sides of said lower portions of said side members of the roofing-sheets below the joint formed between the roofing-sheets, said cap being provided externally with two laterally and outwardly projecting flanges and having the lower portions of its sides diverging downwardly below the joints formed between the cap and the roofing-sheets, the aforesaid lower portions of said side members of the roofing-sheets diverging downwardly between the inner surfaces of the lower portions of the sides of the cap but spaced from said surfaces, the spaces formed at said surfaces between the cap and the roofing-sheets extending from the bottoms of the flanges of the cap upwardly toward the joints formed between the cap and the roofing-sheets.
7. In a car-roof, two metal roofing-sheets having each a side member which has an upright lower portion arranged opposite and spaced from the lower portion of the corresponding side member of the other roofing-sheet, said side members of the roofing-sheets having ogee-curved portions which project from the upper ends of the aforesaid lower portions of said side members toward and into contact with each other; a trough arranged between the opposing sides of and spaced from said lower portions of said side members of the roofing-sheets, and a cap covering said side members of the roofing-sheets and forming joints with the other sides of said lower portions of said side members of the roofing-sheets below the aforesaid ogee-curved portions.
8. In a car-roof, two metal roofing-sheets having each a side member which has an upright lower portion arranged opposite and spaced from the lower portion of the corresponding side member of the other roofing-sheet, said side member of each roof-

ing-sheet having a portion which extends laterally toward the other roofing-sheet and comprises a trough arranged adjacent the upper end of the aforesaid lower portion of said side member of the roofing-sheet; a trough arranged between the opposing sides and spaced from said lower portions of said side members of the roofing-sheets, and a cap covering said side members of the roofing-sheets and forming joints with the other sides of said lower portions of said side members.

9. In a car-roof, two metal roofing-sheets having each a side member which has an upright lower portion arranged opposite and spaced from the lower portion of the corresponding side member of the other roofing-sheet, said side member of each roofing-sheet having a portion extending laterally toward and into contact with the corresponding portion of the other roofing-sheet, said laterally extending portion of said side member of each roofing-sheet having a trough arranged between the aforesaid lower portion of said side member and the joint formed between the roofing-sheets, a trough arranged under the joint formed between the roofing-sheets, and a cap cov-

ering said side members of the roofing-sheets.

10. In a car-roof, two metal roofing-sheets having each a side member which has an upright lower portion arranged opposite and spaced from the lower portion of the corresponding side member of the other roofing-sheet, said side member of each roofing-sheet having a portion extending laterally toward and in contact with the corresponding portion of the other roofing-sheet, said laterally extending portion of said side member of each roofing-sheet having a trough, and adjacent sides of the troughs of said laterally extending portions of said side members of the roofing-sheets being extended upwardly above the passageways formed in and by said troughs and forming a joint between the roofing-sheets; a trough arranged under said joint, and a cap covering said side members of the roofing-sheets.

In testimony whereof, I sign the foregoing specification, in the presence of two witnesses.

JOSEPH A. COSTELLO.
